CLAIM

The ornamental design for an electric shaver, as shown and described.

DESCRIPTION

FIG. 1 is a top and right front perspective view of an electric shaver showing my new design;

FIG. 2 is a front elevational view thereof;

FIG. 3 is a right side elevational view thereof, the left side elevational view being a mirror image of the side view shown;

FIG. 4 is a top plan view thereof;

FIG. 5 is a rear elevational view thereof;

FIG. 6 is a bottom plan view thereof;

FIG. 7 is a cross-section view thereof taken along the line 7—7 in FIG. 2; and,

FIG. 8 is a cross-sectional view thereof taken along the line 8—8 in FIG. 2.
